UNITED STATES PATENT OFFICE.

PAUL E. SABINE AND WILLIAM F. FRIEDMAN, OF GENEVA, ILLINOIS, ASSIGNEES TO
SAID PAUL E. SABINE, AS TRUSTEE.

APPARATUS FOR AND METHOD OF RAPID TRANSMISSION OF TELEGRAPHIC MESSAGES.

Application filed August 7, 1920. Serial No. 401,935.

To all whom it may concern:

Be it known that we, PAUL E. SABINE and WILLIAM F. FRIEDMAN, citizens of the United States, residing at Geneva, Illinois, 5 have invented certain new and useful Improvements in Apparatus for and Methods of Rapid Transmission of Telegraphic Messages, of which the following is a specification.

10 This invention relates to mechanical means for sending and receiving wireless messages and to a new method of carrying out this operation, the purpose being to simplify the work and increase the speed 15 of such transmission of messages; it also relates to apparatus for wireless relaying of signals from one wire system to another, and the method of accomplishing this result; also to the transmission by radio of 20 such impulses as are used for operating high speed printing telegraphs; it is a further object to produce a device by which a message received as if composed of impulses of one kind only, will be translated into impulses of two kinds; and such further objects, advantages and capabilities as will 25 later more fully appear.

Our invention further resides in the combination, construction and arrangement of 30 parts illustrated in the accompanying drawing, and while we have shown therein a preferred embodiment we desire the same to be understood as illustrative only and not as limiting our invention.

35 At present the transmission of code signals by wireless requires two modifications of the transmitting electric current for the formation of letters and symbols of the transmitted messages, while by our invention 40 such transmission may be accomplished with only a single modification. In ordinary telegraphing these modifications consist of dots and dashes produced by short and long periods during which the signalling circuit is closed by the telegraphic key. In the so called stop and start system of the 45 printing telegraph, positive and negative pulses of electric current are made to produce opposite effects upon a receiving relay. It is to the latter system that the 50 present invention is applicable.

We will assume that each one of the letters of the alphabet and the various symbols necessary in telegraphic communication can

be represented respectively by one of the 55 thirty-two possible arrangements of positive and negative impulses of a group of five impulses of both kinds. Indicating a positive impulses by "a" and a negative impulse by "b," combinations by which the 60 letters of the word "the" may be represented, are as follows:

T	H	E
aaaab	aabab	baaaa

65

In the present invention the transmitting device will supply only the positive impulses. During the interval in which the negative impulses would ordinarily be transmitted, the sending mechanism is inoperative, the negative impulses being supplied by the receiving mechanism in a manner to be described later.

70 In the drawings annexed hereto and forming a part hereof, Fig. 1 is a diagrammatic representation of a sending mechanism in accordance with our invention, while Fig. 2 represents diagrammatically the mechanism of the receiving station. The 75 following description and diagrams are 80 specifically for the case in which the energy for the production of signals is transmitted without wires. It applies with slight alteration to the case in which the transmission of energy is by means of electric oscillations 85 along wires, and the response of the receiving apparatus is conditioned upon its being tuned to the frequency of these oscillations.

90 Referring more in detail to the mechanism shown in the drawings, E denotes a generator of radio frequency continuous electromagnetic oscillations connected in the ordinary manner to the antenna circuit of the sending station, the coil S of which is tuned to be in resonance with E. The 95 polarized relay R of the printing telegraph is placed in the antenna circuit, taking the place of the sending key of ordinary hand transmission. This relay R is operated by the positive and negative impulses coming over the line L, in which is located the 100 mechanical sending means. The two positions of the armature of the polarized relay correspond with the two positions of the key in the ordinary method of signalling by 105 dots and dashes, position *n* corresponding to the open key and position *p* to the closed key position.

The mechanism at the receiving end, shown in Fig. 2, will now be considered, in place of the receiving telephone, commonly used, relay R' is substituted. The armature of this relay is normally held in position n' , in engagement with a contact a' so as to close the circuit to line L' through one of the contacts of the rotating device W . When incoming signals energize the solenoid of relay R' , the armature is pulled over into position p' to close the circuit to line L' through the electromagnet M . In each of these circuits is placed a source of current arranged as shown.

15 The generator E supplies continuous electrical oscillations to the antenna, as is obvious, and a negative impulse coming over the line L will draw the armature of relay R to the position n , the contact at a short circuiting a portion of the antenna inductance, altering the frequency and decreasing the amplitude of the electromagnetic waves being radiated. When a positive impulse actuates the relay, the armature is pulled to the position p . The waves will then be radiated with full amplitude, having the frequency of the generator E and the tuned circuit S . An ordinary receiving station with antenna tuned to the 20 frequency E will then receive a series of signals in which the positive impulses coming over the line L are represented by sounds in the telephone receiver, and the negative impulses by silences, because, by 25 the arrangement shown, the negative impulses are not tuned to the frequency E , and will, therefore, not be heard. In other words, so far as the receiving station is concerned, the sending station can transmit only the positive impulses and suppresses the negative impulses. The word "the" will then be represented thus

T   H   E
      aaaa—   aa—a—   —aaa

At the receiving station, the incoming signals, corresponding to the positive impulses of the sending station, pull the armature of the relay R' to the position p' , connecting the line L' to the positive end of a source of electric current. The electromagnet M referred to above, is located in this circuit, and is, therefore, energized only by the positive impulses produced by the 50 incoming signals. The purpose of this electromagnet will appear later.

The rotor W is simply a device by which the line L' is put into contact with the negative end of a battery five times during each 55 revolution of the rotor, provided the armature of the relay R' is on the contact a' corresponding to position n' . The rotor W carries a series of contacts C^1 , C^2 , C^3 , C^4 , and C^5 , spaced 60° apart about the axis of the rotor, the interval between C^1

and C^5 being 120° and corresponding to the interval between letters. Attached to each of these contacts is a piece of soft iron which is acted on by the electromagnet M as the rotor turns past the magnet, provided the armature of relay R' is in position p' . If there is approximate synchronism between the sending and receiving mechanisms, the tendency of the electromagnet M will be to advance or retard the rotor W by attraction of the soft iron pieces. This will, therefore, tend to produce exact synchronism between the sending and receiving mechanisms. Approximate synchronism of these mechanisms may be attained 70 by any one of a number of well known mechanical devices.

The rotor W should be driven at a constant speed by an automatically governed driving mechanism, its speed being adjusted so that the negative impulses imparted to the line L' through the contacts, B and n' are synchronous with the impulses received from the line L at the transmitting station. If we suppose that the letter T is being transmitted, this will be represented by four positive impulses and a negative impulse, which are transmitted by the sending station. Since the positive impulses are transmitted as electrical oscillations of frequency E and the receiving station is tuned to the same frequency these four positive impulses will be picked up by this receiving apparatus, and the negative impulse being at a different frequency will not be picked up. The relay R' will then be energized by four pulses of current followed by a time interval in which no current flows, this being of the length of one pulse, corresponding to the negative impulse. The armature of relay R' will then make four contacts with b' followed by one with a' . The line L' will accordingly receive the four positive impulses and the one negative corresponding to the letter T .

As a modification of the above described apparatus, the single electromagnet M may be replaced by six magnets, spaced at points 60° apart about the axis of rotation of the rotor W . A separate relay, operating a local battery circuit, and connected in series with the solenoid of relay R' , may be provided for energizing the electromagnet M or the substituted six electromagnets in the event that such are used.

It appears that for successful operation two conditions are necessary; first the adjustment of the brushing contact B must be such that it will always touch a moving contact C at such times as it is possible for an electromagnetic impulse to be received to actuate the relay R' . Then at such of these times as there is no electromagnetic impulse actually received there will be a negative impulse supplied to the line L'

through the contacts C, B and a' . The blank position on the rotor, which has no contact, must be at the contact B at the time which corresponds to the interval allowed, by the sending machine, between letters or symbols. This condition is met by proper initial adjustment of the brush B. Second, there must be exact synchronism between the mechanism operating the sending key and the rotation of W. This condition is met as indicated above, by securing an approximate synchronism of sending and receiving mechanisms, by well known mechanical devices, and then securing exact synchronism by means of the action of electromagnet M on the iron pieces secured to the rotor W. If the pulses through M are in exact step with the soft iron pieces attached to the rotor, then the force between the magnet and the iron has no effect either in retarding or accelerating the motion of the rotor. If, however, the position of the soft iron pieces is slightly in advance of the magnet at the instant the incoming signal operates, then the pull of the magnet will retard the rotor W; conversely, if the pole piece is slightly behind the magnet M at the instant of the arrival of the signal, then the force is such as to accelerate the rotor. In this way, the rotor is automatically kept in exact step with the incoming signals. Other methods of securing the same result may be employed.

Plainly L may represent the receiving end of a wire transmission line. It is also the sending end of a wireless system of transmission; similarly L' is the receiving end of a wireless system, and may be the sending end of a wire system. The impulses which actuate the wireless apparatus may originate locally or at a distance, and thus transmitted along L' may be received locally or at a distance. Therefore our invention provides a means by which messages may be directly and automatically relayed by wireless from one wire system to another wire system.

It appears also that the apparatus and the method are applicable to any wire system of telegraphy in which the transmission of energy for producing the signals is by means of electric oscillations and in which the response of the receiving apparatus is conditioned upon its being tuned to the frequency of such oscillations. Therefore, while the foregoing description and diagrams have referred specifically to the case in which the electromagnetic oscillations are transmitted without wires, they apply equally to the case in which these oscillations are carried on wires and the application to the latter is a part of our invention.

It is, of course, understood that the specific description of structure and methods set forth above may be departed from with-

out departing from the spirit of our invention as set forth in this specification and the appended claims.

Having now described our invention, we claim:

1. In telegraphic systems comprising a transmitting means operating with two different kinds of impulses and transmitting only one kind thereof to a receiving means, and receiving means supplying the untransmitted kind of impulses whereby the receiving means operates with two different kinds of impulses similar to these with which the transmitting means operated.

2. In apparatus for transmitting messages comprising sending and receiving devices, said sending device having a generator of electro-magnetic oscillations, a tuned circuit, means operating with two kinds of impulses and having means for suppressing one of said kinds of impulses, means to transmit the other of said kinds of impulses as electro-magnetic waves of a definite frequency and amplitude capable of effecting the operation of the receiving device.

3. In apparatus for transmitting messages comprising sending and receiving devices, said sending device having a generator of electro-magnetic oscillations, a tuned circuit, means operating with two kinds of impulses and having means for suppressing one of said kinds of impulses, means to transmit the other of said kind of impulses as electro-magnetic waves at definite frequency and amplitude capable of effecting the operation of the receiving device, said receiving means supplying the untransmitted kind of impulses whereby the receiving means operate with two different kinds of impulses similar to those with which the transmitting means operated.

4. In apparatus for transmitting messages comprising sending and receiving devices, said sending device having means for producing and transmitting tuned electric oscillations by means of a suitable medium, means for impressing a selected kind of impulses of different kinds of impulses upon the transmitting means whereby the receiving device operates with like impulses, said receiving means having means for supplying impulses of a different kind, whereby the receiving means operates with different kinds of impulses similar to those with which the sending device operated.

5. In apparatus for transmitting messages comprising sending and receiving devices, means operating with impulses of different kinds and causing a selected kind thereof to be transmitted by the sending device to the receiving device, means for causing the receiving device to furnish impulses corresponding to the different kinds of impulses operating in the sending device.

6. In an apparatus for transmitting mes-

5 sages comprising sending and receiving devices, said sending means having means for transmitting electrical energy to the receiving device by means of a suitable medium capable of transmitting electric oscillations, means operating with two different kinds of electrical impulses and to suppress one thereof and to impress the other thereof upon the transmitted energy, and means to cause the receiving device to furnish two kinds of impulses similar to those operating in the sending device.

10 7. In an apparatus for transmitting messages comprising sending and receiving devices, said sending means having means for transmitting electrical energy to the receiving device by means of a suitable medium capable of transmitting electro-magnetic oscillations, means operating with two different kinds of electrical impulses and to suppress one thereof and to impress the other thereof upon the transmitted energy, and means to cause the receiving device to supply impulses corresponding to two kinds 15 of impulses operating in the sending device, the last named means including means for synchronizing the receiving device with the sending device.

20 8. In an apparatus for transmitting messages comprising sending and receiving devices, said sending means having means for transmitting electrical energy to the receiving device by means of a suitable medium capable of transmitting electro-magnetic oscillations, means operating with two different kinds of electrical impulses to suppress one thereof and to impress the other thereof upon the transmitted energy, and means to cause the receiving device to supply impulses corresponding to two kinds of impulses operating in the sending device, the last named means having means for substantially synchronizing the receiving device with the sending device, and means for automatically adjusting the synchronizing means to effect exact synchronism with the sending device.

25 9. In apparatus for transmitting messages comprising sending and receiving devices, said sending device having means for radiating electro-magnetic oscillations, said oscillations being transmitted by a suitable medium to the receiving device, means for modifying the frequency of said oscillations, said modifications being affected by a succession of two kinds of impulses, said receiving device having means for reproducing impulses of the kind that effected the transmission of the unmodified oscillations, and means for supplying impulses like those that modified the frequency of the electro-magnetic oscillations.

30 10. In apparatus for transmitting messages comprising sending and receiving devices, said sending means having means for

receiving two different kinds of impulses, means for transmitting only one kind of said impulses to the receiving device, said receiving device reproducing the other kind of impulses whereby the received and reproduced impulses effect recording of impulses in accordance with the impulses received by the sending device.

35 11. In apparatus for transmitting messages comprising a generator of electrical oscillations, means for transmitting said oscillations, means for modifying parts of said oscillations, said means being affected by different kinds of impulses and effecting non-transmission of a kind of said impulses at the instants of effecting said modifying of said parts of said oscillations.

40 12. The method of transmitting and recording messages, consisting of transmitting one of two different kinds of impulses, receiving the transmitted kind of impulses, and reproducing the other kind of impulses whereby impulses of two kinds are recorded.

45 13. The method of transmitting and recording messages, consisting of transmitting one of two different kinds of impulses and of modifying the frequency and amplitude of electro-magnetic oscillations by the other kind of impulses so that they will not be received by a receiving device receiving the transmitted impulses and automatically supplying impulses corresponding to the modified impulses in the sending device.

50 14. In apparatus of the class described, mechanism for producing impulses of two kinds, means for producing electro-magnetic oscillations corresponding in time location to these two kinds, but having different frequencies and amplitudes, means for transmitting and receiving impulses corresponding to one of said kinds, and means connected with the receiving means for automatically supplying impulses corresponding in time location to the impulses not received and of the other of said kinds.

55 15. The method of relaying signals from one wire system to another wire system by wireless apparatus, which comprises transmitting from one of the wire systems, to the wireless sending apparatus, impulses of two kinds, radiating by one kind of impulses electro-magnetic waves of a frequency that will actuate the wireless receiving apparatus, radiating by the other kind of said impulses electro-magnetic oscillations of such frequency and amplitude as will not be received by the wireless receiving apparatus, supplying by the receiving mechanism of the wireless system, impulses of the second kind, and transmitting to the second wire system impulses of both kinds, corresponding in time location to those of the first wire system.

60 16. In apparatus for transmitting messages comprising a generator of electro-

magnetic oscillations, means affected by impulses of different kinds and operating to modify the amplitude of said oscillations upon the affecting of said means by one kind 5 of said impulses.

17. In apparatus for transmitting messages comprising means for effecting successive impulses consonant with electro-magnetic oscillations received by said means 10 from a sending device, and means for supplying impulses corresponding in time loca-

tion to impulses affecting the sending device but not received by the receiving device.

In witness whereof, we hereunto subscribe our names to this specification in the presence of two witnesses. 15
